UNITED STATES PATENT OFFICE.

FREDERICK W. LINAKER AND THEODORE M. BRUBACK, OF DUBOIS, PENNSYLVANIA.

TUBE CLEANER.

1,408,369.

Specification of Letters Patent. Patented Feb. 28, 1922.

Application filed April 21, 1919. Serial No. 291,545.

To all whom it may concern:

Be it known that we, FREDERICK W. LINAKER and THEODORE M. BRUBACK, the former a subject of the King of Great Britain and the latter a citizen of the United States of America, both residing in Dubois, in the county of Clearfield and State of Pennsylvania, have invented certain new and useful Improvements in Tube Cleaners, of which the following is a specification.

This invention relates to devices for cleaning the tubes of boilers, economizers, and the like, commonly known as soot cleaners, and aims to provide improvements therein.

The present invention provides a tube cleaner for boilers, attached to a fitting upon the setting or wall of the boiler, and adapted to be projected into the interior of the boiler setting when it is desired to clean the tubes, and to be withdrawn from the interior of the boiler setting when the cleaner is not in use. The removability of the cleaning element from the interior of the setting is of especial advantage where the position of the cleaning element or tube in the interior of the boiler setting is adjacent the combustion chamber of the furnace, or in the first passes for the combustion gases through or over the tubes.

The cleaning element or tube is also preferably disposable, in its withdrawn position, alongside of the boiler, in such manner as to be out of the way of persons around the boiler.

The invention further provides a simple, durable, and efficient construction.

Other features of the invention will be hereinafter more fully set forth.

Two embodiments of the invention are illustrated in the accompanying drawings:

Figures 1 to 3, inclusive, illustrate one embodiment, and Figs. 4 to 6, inclusive, illustrate another embodiment.

Figure 1 is a vertical sectional view of said first embodiment, attached to the wall or setting of a boiler;

Fig. 2 is a horizontal sectional view of certain of the parts shown in Fig. 1;

Fig. 3 is a sectional view on the line III—III, Fig. 1, looking in the direction of the arrows;

Fig. 4 is a vertical sectional view of the second embodiment, shown attached to the wall or setting of a boiler;

Fig. 5 is a horizontal sectional view of certain parts shown in Fig. 4;

Fig. 6 is a view in elevation of the parts shown in Fig. 4;

Figs. 7 and 8 are views illustrating the manner of use, and disposal when not in use, of the parts of the invention.

The embodiment illustrated in Figs. 7 and 8 is that of Figs. 1 to 3, inclusive. In the embodiment shown in Figs. 4, 5 and 6, the cleaning tube is projected into the interior of the setting, and withdrawn, and disposed, when not in use, similarly to the parts shown in Figs. 7 and 8, although in the construction shown in Figs. 4, 5 and 6, the cleaning element or tube may be swung to and fro in the interior of the setting, as will hereinafter more fully appear.

Referring to Figs. 1, 2 and 3, numeral 1 designates a cleaner pipe or element, and 2 a fitting through which said cleaner pipe or element extends, and in which it may be slid into and out from the interior of the boiler setting.

The fitting 2 preferably comprises a plate 3, adapted to be fastened to the wall or setting of a boiler, and having brackets 4, 4', on which a box 5 is pivotally mounted, as indicated at 6, 7.

The box 5 is provided with a stuffing box 9 adapted to prevent the escape of cleaning fluid around the cleaner tube, and in which the cleaner tube or element 1 is slid back and forth. The box 5 is also provided with a bearing 10 for the cleaner tube. The stuffing box 9 is preferably connected to the box 5 through a short pipe extension 12, in order to give the cleaner tube or element a longer bearing between its supports.

15 designates a cleaning fluid supply pipe, connected with the box 5 through a swinging packing joint 17. The cleaning fluid may be any fluid useful for this purpose, but is usually steam. A nipple or short piece of pipe 19 may be interposed between the swinging packing joint 17 and the box 5, and constitute one of the pivots upon which the box 5 turns.

The box 5 is provided with a steam chamber 21, surrounding the cleaner pipe or element 1, and the cleaner pipe or element 1 is provided with steam inlet openings 23 adapted to admit steam from the chamber 21 to the interior of the pipe 1, when the pipe is projected into the interior of the boiler setting, as indicated in Fig. 1 (and 110 as indicated in dotted lines in Fig. 7).

The part of the cleaner pipe or element

1 which projects into the interior of the boiler setting, is provided with a plurality of jet-forming orifices 24 (Fig. 7), through which the cleaning fluid is adapted to issue 5 in jets, and strike against the tubes or other parts of the boiler to be cleaned, and thereby dislodge the soot or other extraneous matter from the tubes.

The cleaner pipe or element 1 is provided 10 with a handle 25, which may be used in sliding the cleaner pipe to and from the interior of the boiler, and, when the tube or element 1 is projected into the interior of the boiler setting, the handle 25 may be 15 used to turn the tube or element on its axis and thereby direct the jets in various directions, so as to secure a thorough cleaning of all parts of the interior of the boiler within the reach of the jets.

20 The boiler setting or wall is provided with a passage 27 through which the cleaner pipe or element passes. The box 5 and the plate 3 fit closely, so as to shut off the entrance of air into the interior of the boiler setting. 25 This close fit between the parts 3 and 5 is best secured by using a packing 29 between them.

The face 30 of the box 5 facing the plate 3, is preferably circular in cross-section, and 30 the face 31 of the plate 3 is correspondingly shaped. These corresponding circular faces permit the box to be turned upon its axis 6, 7, a quarter turn or so, and still keep covered the passage 27 leading to the interior 35 of the boiler setting.

Operation: Normally the cleaner tube or element is in the position shown in Fig. 8, alongside the wall or setting of the boiler. See also the position indicated by the dotted 40 line 33, Fig. 7. In this position the inner end 35 of the cleaner tube or element is flush with or slightly below the face 30 of the box 5. In order to use the device for cleaning, the tube 1 and box 5 are swung 45 around the axis 6, 7, of the box until the end 35 of the tube is in line with the opening 27 in the wall of the boiler, Fig. 7. The cleaner tube or element 1 is then pushed into the interior of the boiler to an extent 50 sufficient to bring the inlet openings 23 into the chamber 21 of the box. Steam may thereupon be admitted through the pipe 15, and this steam passes through the nipple 19 into the chamber 21, through the inlets 23 55 to the interior of the pipe, and thence through the jet-forming orifices 24 onto the parts to be cleaned. The surfaces struck by the jets may be changed by turning the cleaner pipe or element 1 upon its axis.

60 To remove the cleaning pipe or element after the cleaning has been effected, and to prevent the corrosion of the cleaning pipe or element, and also damage thereof by heat, the cleaning pipe or element is pulled outwardly through the box 5 to the position 65

shown in full lines, Fig. 7. The end 35 of the pipe being flush with or slightly below the surface 30 of the box 5, the cleaner pipe is swung against the wall of the boiler, the box turning on its axis 6, 7, and left in such 70 position. A support 37 may be provided upon the wall of the boiler to hold the projecting end of the cleaner pipe or element 1, as indicated in Fig. 8.

Referring to Figs. 4, 5 and 6, numeral 1 75 designates the cleaning pipe or element provided with inlet orifices 23 and jet-forming orifices 24. Numeral 5 designates the box turning on the pivotal axis 6, 7, and provided with the steam chamber 21, stuffing 80 box 9, bearing 10, and swinging packing joint 17, all of which parts may be similar in construction to the correspondingly numbered parts in Figs. 1 to 3 of the drawing.

50 designates a plate having arms or 85 brackets 51, 52, in which the box 5 is mounted, and having a curved or circular face 54 similar in curvature to the face 30 of the box 5. A packing 56 is preferably provided between these faces 30 and 54. 90

The cleaner tube or element 1, in the embodiment shown in Figs. 4, 5 and 6, is adapted to be swung or oscillated on the interior of the boiler setting. To this end the boiler setting or wall is provided with an opening 95 58, elongated in the direction in which it is desired to swing the cleaning tube or element 1. A guide 60 may be provided for the outer end of the cleaner pipe or element, and the cleaner pipe or element provided with a shoe 61 adapted to slide on said guide 60. The face of the shoe 61 which slides upon the guide 60, is flat, and thereby prevents the cleaner tube or element being turned upon its axis. However, the ends of 105 the guide are cut away slightly, as indicated at 63, so that when the shoe is swung to the extreme ends of the guide, the cleaner pipe or element 1 may be turned slightly upon its axis. 110

The shoe may be provided with a shoulder 65 for limiting the inward movement of the cleaner tube or element in the box 5.

Handles 67, 68, may be provided for convenience in sliding and turning the cleaner 115 tube or element 1.

The embodiment of the invention shown in Figs. 4 to 6 is of especial advantage in connection with vertical fire tube boilers.

Operation: When not in use, the cleaner 120 tube or element 1 is withdrawn from the interior of the boiler setting, and preferably disposed alongside of the boiler setting similarly to the cleaner tube 1 shown in Fig. 8. The end 35 of the cleaner tube is flush with, 125 or slightly below, the surface of the box 5.

When it is desired to use the device to clean the tubes or other parts on the interior of the boiler, the cleaner tube or element 1 is swung out into line with the opening 58 130

in the boiler wall or setting, the box turning upon its pivotal axis 6, 7. When in line with the opening 58, the cleaner tube or pipe is pushed or slid inwardly to the position where the inlet orifices 23 are in communication with the chamber 21 in the box 5. This extent of movement may be determined by the stop or shoulder 65. Steam, or other fluid, may then be admitted through the pipe 15, passing therefrom into the chamber 21, and thence into the element or tube 1 through the orifices 23, and out from the tube, in jets, through the jet-forming orifices 24. The cleaner tube or element may be swung upon the axis 6, 7, in order to cause the jets to strike against different parts on the interior of the boiler setting, and at the ends of the guide 60 the tube or element 1 may be swung slightly on its axis, thereby directing the jets upon other parts on the interior of the boiler setting.

After the cleaning has been effected, the cleaner tube or element 1 is pulled outwardly until its end 35 is flush with, or below, the surface 30 of the box 5, whereupon the tube may be swung against or alongside the side of the boiler or setting, the box 5 turning upon its axis 6, 7. When withdrawn from the interior of the boiler setting, and disposed alongside of the wall or setting, the cleaner is out of the way of the boiler attendants, and liability to damage by heat and corrosion is greatly minimized.

The inventive ideas herein set forth may receive other embodiments than those herein specifically illustrated and described.

What we claim is:—

1. A tube cleaner, or the like, comprising a cleaner tube, and a pivotal support therefor, mounted outside the wall of the boiler furnace, said cleaner tube having a cleaning fluid passage, and jet forming orifices therein, said tube being slideable in said support, and adapted, when slid out, to swing on the axis of said support into a position alongside the wall of the structure.

2. The combination with a boiler, or the like, having an opening through its structural wall, of a fitting covering said opening, a rotatable support pivotally mounted in said fitting, and a cleaner tube slideable in said support, said cleaner tube having a cleaning fluid passage, and jet forming orifices therein, said support having its axis at the outer side of the wall, whereby said cleaner tube, when slid in said support to its outermost position, may swing, with said rotatable support, to a position alongside said wall.

3. The combination with a boiler, or the like, having an opening through its wall or setting, of a fitting covering said opening, a rotatable support pivotally mounted in said fitting, having an internal chamber, an admission pipe for introducing cleaning

fluid to said chamber, and a cleaner tube slideable in said support, said cleaner tube having a cleaning fluid passage, and jet forming orifices therein, said tube having an inlet opening which, in its operative position, admits fluid from said chamber to said passage in said tube. 70

4. The combination with a boiler, or the like, having an opening through its wall or setting, of a fitting covering said opening, a rotatable support pivotally mounted thereon and having an internal chamber, means for introducing a cleaning fluid into said chamber, and a cleaner tube slideable through said support, the latter having means for making a tight joint between said tube and support in operative position, said cleaner tube having a cleaning fluid passage, and jet forming orifices therein. 75 80

5. A tube cleaner, or the like, comprising a fitting, adapted to be applied to the boiler wall a rotatable support pivotally mounted on said fitting, on an axis parallel with said wall a cleaner tube slideable through said support, and a swivel connection for admitting 85 cleaning fluid to said support, formed concentrically with the pivotal axis thereof, said cleaner tube having a cleaning fluid passage, and jet forming orifices therein. 90

6. A tube cleaner, or the like, comprising a fitting, a rotatable support pivotally mounted thereon, and a cleaner tube passing through said support, slideable therein, and mounted to be rotated therein, said cleaner tube having a cleaning fluid passage, and 95 jet forming orifices therein, said support having its axis at the outer side of the wall, whereby said cleaner tube, when slid in said support to its outermost position, may swing, with said rotatable support, to a position 100 alongside said wall. 105

7. A tube cleaner according to claim 6, having packing means between the tube and support, adapted to prevent leakage of the fluid between them, while permitting said 110 movements of the tube.

8. A tube cleaner, or the like, comprising a fitting, a rotatable support pivoted thereon, a cleaner tube passing through said support and rotatable therein, and means for 115 admitting cleaning fluid to said tube, said cleaner tube having a cleaning fluid passage, and jet forming orifices therein, said support having its axis at the outer side of the wall, whereby said cleaner tube, when 120 slid in said support to its outermost position, may swing, with said rotatable support, to a position alongside said wall.

9. A tube cleaner, or the like, according to claim 8, having a guide for directing the 125 movement of the cleaner tube around the pivotal axis.

10. A tube cleaner, or the like, according to claim 8, having guiding means adapted to prevent rotation of the cleaner tube, while 130

swinging through a determined arc around the pivotal axis.

11. A tube cleaner, or the like, according to claim 8, having guiding means, comprising a stationary, arc-shaped guide, and a guiding head on the tube, adapted, by their engagement, to prevent rotation of the tube, while swinging through a determined arc around the pivotal axis.

10 12. A tube cleaner, or the like, according to claim 8, having guiding means, comprising a stationary, arc-shaped guide, and a guiding head on said cleaner tube, said guiding means having co-operating parts which prevent rotation of said tube, while swinging through a determined arc, said guiding means permitting oscillation of said tube beyond the limits of said determined arc.

20 13. A tube cleaner, or the like, according to claim 8, having guiding means, comprising a stationary, arc-shaped guide, having a plane guiding face, and having inclined portions beyond such face, and the cleaner tube having a head with a reciprocal guiding face, adapted, through the engagement of said head with said plane face, to guide the tube, in its swinging movements, over a certain arc, and prevent its rotation, and adapted, during its engagement with said 25 inclined portions beyond said arc, to permit it a limited rotation.

30 14. A tube cleaner, or the like, comprising a support mounted on a pivotal axis, having an internal chamber, and means for admitting cleaning fluid to said chamber, a cleaner tube slideable in said support, having an opening communicating with said

chamber when in operative position, and stops to limit the sliding movement of the tube, adapted, when in operative position, to insure communication of said opening with said chamber, said cleaner tube having a cleaning fluid passage, and jet forming orifices therein.

15. A boiler tube cleaner, comprising a support pivotally mounted outside the wall of the boiler furnace, on an axis parallel to said wall, a cleaner tube passing through said wall and through said support and rotatable therein, and slideable in said support outwardly of the furnace, said support and tube adapted, when the tube is in its outermost position, to be turned to bring the tube alongside the wall of the furnace, and means for introducing cleaning fluid into and through said tube into the furnace, when the tube is slid into its operative position in the furnace.

16. The structure of claim 15, the tube and support having spaced stop shoulders adapted to limit the outward sliding of the tube.

17. The structure of claim 15, the support having a chamber receiving the cleaning fluid, and the tube having an opening which, in the operative position only of the tube, communicates with said chamber, whereby the outward sliding displacement of the tube cuts off the flow of cleaning fluid to said tube.

In witness whereof, we have hereunto signed our names.

FREDERICK W. LINAKER.
THEODORE M. BRUBACK.
